UNITED STATES PATENT OFFICE.

JOSEPH SAILER, OF OXNARD, CALIFORNIA.

SEPARATOR.

1,171,891.

Specification of Letters Patent. Patented Feb. 15, 1916.

Application filed December 10, 1914. Serial No. 876,450.

To all whom it may concern:

Be it known that I, JOSEPH SAILER, a citizen of the United States, residing at Oxnard, in the county of Ventura and State of California, have invented a new and useful Separator, of which the following is a specification.

This invention comprehends improvements in separators and relates more particularly to what I term a hydrotrash separator.

The machine is particularly designed for use in separating beet chips and small fragments of beets from leaves, tops and other matter with which they are mixed.

In the beet sugar industry there is a large production of what is known as "trash," this trash consisting of leaves and other foreign matter. This trash is commonly mixed with small pieces of beets, beet tails, and tops. The proportion of beets contained in the trash is quite considerable, and the loss to a sugar beet factory through the discarding of masses of trash amounts to a considerable amount. By the use of my invention it is possible to separate small pieces of beet, tailings, and chips, from the trash, the valuable portions of the beets being afterward utilized so that considerable savings are effected thereby.

One of the objects of the invention is to provide a water separator comprising a tank into which the trash is dumped, and means for setting up water currents which will float the leaves and stems and discharge them over the overflow edge of the tank and which will carry the valuable portions of the trash toward the center of the machine where they are picked up by a conveyor.

With these, and other objects, in view, the invention consists in certain features of construction, combination and arrangement of parts as will be hereinafter described, illustrated and claimed.

Figure 1 is a top plan view of the separator; Fig. 2 is a side elevation, partly broken away and partly in section; Fig. 3 is an end elevation of the separator showing conveying means for the trash; Fig. 4 is a transverse sectional view taken through Fig. 2 on a line midway between the center and the extreme right end of the trough shown.

Referring in detail to the drawings by numerals: 1 designates as an entirety the tank which, it will be understood, may be

made of any size desired and which is preferably formed of sheet metal having downwardly and inwardly converging sides 2, a semi-cylindrical, concavo-convex bottom 3, and end walls 4. A reinforcing flange 5 encompasses the upper edge of the tank on three sides thereof and the fourth side is cut away to form an overflow edge 6 which is disposed below the level of the top of the tank.

A perforated agitating pipe 7 extends longitudinally through the center of the tank in such a position that it is approximately in the center of the mass of trash which is carried in the tank. The agitating pipe 7 is flanged at one end, as indicated by the numeral 8 and bolted to a flange 9 on a revoluble hub 10 which is driven by a belt wheel 11. The other end of the agitating pipe 7 projects into a stuffing box 12 and water or air may be forced into this open end by means of a pipe 13 having a valve 14.

At one end of the tank below the pipe 7 is provided a fitting 15 having a water inlet 16 and a flushing valve 17. This fitting opens into the tank near the bottom thereof and serves either as a means for injecting water into the tank or drawing water therefrom. At the other end of the tank in line 85 with the fitting 15 a water inlet 18 is provided so that water may be forced therethrough toward the center of the tank along the bottom thereof.

To provide for setting up a current of water flowing toward the overflow edge 6 I employ a horizontal trash moving pipe 19 which extends longitudinally of the tank and which is positioned near the rear wall. This pipe is connected at its open end to one end of the tank by a coupling 20 and this open end is fed by a pipe 21 equipped with a valve 22. Pipe 19 has a series of openings 23 formed therein, this pipe being so located, and the perforations 23 being so placed, that a stream of fluid ejected through the perforations 23 will act on the upper part of the mass of trash for the purpose of moving the trash across the tank and through the overflow opening.

The heavier particles composed of small pieces of beet, beet tails, and chips which fall to the bottom of the tank and which are caused to gather at the center thereof by incoming streams of water flowing through the inlet 18 and fitting 15 are carried away by means of a spiral conveyer 24. This con-

veyer extends upwardly at any suitable angle and is incased in a water tight housing or casing 25 which encircles a discharge opening 26 formed in the bottom of the tank. The lower end of the conveyer shaft 27 revolves within a thrust bearing 28 as fully shown in Fig. 4. The casing 25 is preferably provided with a clean-out door 29 on its lower side near its lower end.

10 In operation the mixture of trash, beet tailings, and chips is conveyed to the tank 1 by any suitable means such as the endless conveyer 30 and dumped into the open top of the tank. Water flowing into the tank 15 through the fitting 15 and intake 18 will cause a current toward the center of the tank which will carry the heavy particles as they fall downwardly toward the discharge opening 26. The upward force of 20 the current of water from the fitting 15 and the intake 18 holds the trash in suspension, but this force is not sufficient to hold the heavier particles, consisting of beet tailings and chips, these beet tailings and chips falling 25 to the bottom of the tank. The revolving hollow shaft 7 will cause the water discharging into the tank through the perforations therein to set up an agitation within the tank which will tend to separate the 30 leaves, stems and other light matter from the heavier particles of beets, and the water issuing from the perforations 23 in the pipe 19 will set up a current toward the overflow edge so that the light particles are discharged thereover with the overflow of 35 water.

It will be understood that air may be forced into the tank to the pipes if desired and the currents of air will cause a proper 40 agitation of the water so as to separate leaves and stems from the heavier particles.

From the foregoing description taken in connection with the accompanying drawings, it will be apparent that I provide a 45 very simple and practical separator and it will be understood that changes in construction and arrangement of parts may be made without sacrificing any of the vital features of the invention, provided of course, that 50 such changes fall within the spirit and scope of the appended claims.

Copies of this patent may be obtained for five cents each, by addressing the "Commissioner of Patents, Washington, D. C."

What I claim is:

1. In a separator for removing pieces of beet from trash in the manufacture of beet sugar, the combination of a tank in which 55 the trash is immersed in water, said tank having one side slightly lowered to form an overflow edge, means for agitating the trash in said tank, means for forcing waste matter from said trash over said overflow edge, and 60 means for withdrawing pieces of beet from the center of the tank.

2. In a separator for removing pieces of beet from trash in the manufacture of beet sugar, the combination of a tank in which 65 the trash is immersed in water, said tank having one side slightly lowered to form an overflow edge, a perforated agitating pipe extending through the center of said tank, means for forcing a fluid through the perforations in said pipe to agitate the mass of trash in said tank, means for forcing waste matter from said trash over said overflow edge, and means for forcing the pieces of beet that settle to the bottom of the tank 70 toward a discharge opening through which said pieces are withdrawn.

3. In a separator for removing pieces of beet from trash in the manufacture of beet sugar, the combination of a tank in which 80 the trash is immersed in water, said tank having one side slightly lowered to form an overflow edge, means for agitating the trash in said tank, a trash moving pipe extending across said tank at a point opposite said 85 overflow edge, said trash moving pipe having trash moving perforations therein on the side toward the overflow edge, means for forcing a fluid through said trash moving perforations in such a manner as to 90 force the lighter portions of said trash over the overflow edge, and means for withdrawing pieces of beet from the center of the tank.

In testimony whereof, I have hereunto set 95 my hand, at Los Angeles, California, this 4th day of December, 1914.

JOSEPH SAILER.
